(57) **CLAIM**

The ornamental design for a light emitting diode illumination device, as shown and described.

DESCRIPTION

FIG. 1 is a perspective view of a light emitting diode illumination device showing our new design;

FIG. 2 is a front view thereof;

FIG. 3 is a top view thereof;

FIG. 4 is a right side view thereof;

FIG. 5 is a rear view thereof; and,

FIG. 6 sectional view taken along line 6—6 in FIG. 2 with the internal parts omitted.

A left side view and a bottom view of the design are mirror images of the right side view and the top view, so that the left side view and the bottom view have been omitted.
